UNITED STATES PATENT OFFICE.

FREDERICK G. SARGENT AND ALLAN C. SARGENT, OF GRANITEVILLE,
MASSACHUSETTS.

SQUEEZE-ROLL.

SPECIFICATION forming part of Letters Patent No. 292,257, dated January 22, 1884.

Application filed October 14, 1882. (No model.)

To all whom it may concern:

Be it known that we, FREDERICK G. SARGENT and ALLAN C. SARGENT, of Graniteville, in the county of Middlesex and State of Massachusetts, have invented a new and useful Improvement in Squeeze-Rolls for Squeezing and Drying Fiber, of which the following is a specification.

Our invention relates to squeezing and compressing rolls for squeezing and drying wool and other fibrous materials after being washed or soaked; and it consists in a novel attachment to produce the compression of such rolls, substantially as hereinafter described.

15 In the drawings, Figure 1 is a side view of a squeeze-roll frame and rolls provided with our invention. Fig. 2 is a section through line *x y* of Fig. 1.

A is the frame of the machine.

20 *B B* are the squeeze-rolls.

C is a feed-apron by which the fiber is carried to the rolls.

a a are the rollers which carry the feed-apron.

25 *c c* is a pair of levers pivoted at *b* and resting on the upper side of the boxes of the upper squeeze-roll. On the upper sides of these levers, near their outer ends, are a series of projections, *d d*, being opposite to each other when the levers are in place in the machine.

30 *a'* is a bar, of metal or other suitable material, having in its lower side two depressions, *c' c'*, into which the projections *d d* fit. By the construction and arrangement of this bar *a'*, as described, a superior and equalizing action of the weights *g g* upon the upper roll, *B*, is secured, as well as a much cheaper and more durable construction of the several parts.

35 This equalization of the weights upon the upper roll, *B*, is produced by the bearing-point of the bar *a'* upon each lever *c* being placed between the points on said bar when the weights exert their pressure upon said bar

40 near each end by means of the levers *l l* and connecting-rods *e e*. It is obvious that with this construction a proportional part of the pressure of each weight will be exerted upon the same lever *c*, and thus tend to equalize

the pressure upon both ends of the roll *B*, 50 which is important when the wool passes under the roll in greater quantities or masses near one end than near the other, as is frequently the case in practice. In order to facilitate this action of the combined parts the 55 conoidal-pointed nuts *b' b'* and their corresponding sockets in the bar *a'* are used as well as the notches *c' c'* and corresponding beveled edges of the levers *c c*, passing through them. The construction of the parts prevents binding between the rods *e e* and bar *a'*, or between the levers *c c* and bar *a'*, the equalizing-pressure of the weights having full effect when one end of roll *B* is raised higher than the other by reason of a greater mass of fiber 60 passing under the roll near that end.

Through holes in the ends of the bar *a'* rods *e e* extend and project downward nearly to the base of the machine. These rods have threads cut upon their upper ends, upon 70 which nuts, connected with the hand-wheels *b' b'*, are fitted, these nuts being egg-shaped at their lower ends where they come against the bar *a'*. The shape of these nuts allows the free movement of the rods *e e* in the bar *a'* as 75 it works up and down.

e' is a spiral spring resting on the bar *a'*, and serving to assist in compressing the rolls. At their lower ends the rods *e e* are provided with stirrups *m m*, surrounding the levers *g g*. 80 The stirrups fit into notches *l l* in the lower sides of the levers, and by moving them from one notch to the other a greater or less compression is produced, as desired. By combining the shifting of the bar *a'* upon the different pairs of projections *d d*, with this shifting of the stirrups in the notches *l l* any desired degree of compression can be produced.

85 The levers *g g* are pivoted to the frame at *n*, and have weights hung on their outer ends, 90 as shown.

The squeeze-rolls may be used separately, as shown, or may be applied to a wool-washing or other similar machine in which it is desired to squeeze or compress the fiber.

95 What we claim as new and of our invention, is—

1. In combination with the squeeze-rolls *B*

and levers *c c*, the bar *a'*, rods *e e*, and levers *g*, substantially as described.

2. In combination with the roll *B*, the bar *a'*, provided with depressions *c' c'*, and the levers *c c*, provided with projections *d d*, fitting said depressions, substantially as described.

3. In combination with the levers *c c*, the bar *a'*, the roll *B*, the conical or egg-shaped

nuts *b'*, rods *e*, and levers *g*, substantially as described.
